G. G. RONA

HOLDER FOR SHOES

Filed June 23, 1926

UNITED STATES PATENT OFFICE.

GUSTAVE G. RONA, OF NEW YORK, N. Y.

HOLDER FOR SHOES.

Application filed June 23, 1926. Serial No. 117,939.

The object of this invention is to provide a sectional shoe holder which shall be light, preferably flexible, inexpensive to manufacture and of such forms that one or any desired succeeding sections may be employed. The device is adapted to hang on a door-wall or other support and sections may be applied to the whole without disconnecting any of the preceding sections.

10 The invention will be understood by reference to the accompanying drawings, in which—

Figure 1 is a plan view of two connected sections, the lower section being broken away, the device being shown in its preferred form;

Figure 2 is a view similar to Figure 1, showing a modified form of the device;

Figure 3 is a transverse section on the line 3—3, Figure 1, looking in the direction of the arrows;

Figure 4 is a section on the line 4—4, Figure 1, and

Figure 5 is a section on the line 5—5, Figure 2.

In the preferred form of the device, as illustrated in Figure 1, it comprises a backing member 1 which is preferably formed of cloth. The said backing member has stitched thereto a cloth-piece 2 in such manner that a central line of stitching 3 running longitudinally of the backing and the longitudinal lines of stitching 4 and 5 provide pockets A, B. In order to give the pockets capacity 35 with a minimum width of the fabric backing 1, the cloth-piece 2 is fulled or folded in any desired manner, as for example in the manner shown in the cross section, Figure 3.

In order to give strength to the holder, I 40 preferably place the side and bottom edges of the cloth-piece 2 under a tape 6 and form the stitches 4 and 5 through the tape. If desired, a further line of stitching 7 may be formed at the bottom of the cloth-piece 2 45 and such stitches extending through the backing member 1.

At the bottom of the cloth-piece 2, extending through the same and through the backing, is the eyelet b^* of a hook member b , two of said members being preferably employed, 50 one at each side margin of the device. At the top of the device I provide two complementary interlocking members, said members being eyelets c which are adapted to coact with the bottom interlocking members of 55 a preceding section.

In the modification illustrated in Figure 2, the construction is substantially the same as in the preceding figure, with the exception that the complementary interlocking members 60 are of different construction. At the top of the device they are socket members d and at the bottom of the device they are headed members e adapted to enter the sockets d and be held therein by spring engagement, the ordinary socket fasteners being 65 employed.

It will be understood that I do not limit myself to the exact forms of complementary interlocking members employed to hold succeeding sections together, what I claim and desire to secure by Letters Patent being as 70 follows:

In a sectional shoe holder, a backing member of cloth, a cloth-piece superposed thereon 75 and connected approximately at its centre to the backing with a longitudinal line of stitching, a folded piece of material at the side margins and bottom of the holder and enclosing the edges of the said two cloth 80 members and stitched thereto, and a plurality of interlocking members at the top and at the bottom of the holder, the said interlocking members at the bottom being adapted 85 to coact with the top locking members of a succeeding holder.

In testimony whereof, I have signed my name to this specification.

GUSTAVE G. RONA.
